UNITED STATES PATENT OFFICE.

FRANK S. WAHL, OF NORTH TONAWANDA, NEW YORK.

INTERNAL-COMBUSTION ENGINE.

Original application filed November 30, 1917, Serial No. 204,571. Divided and this application filed March 27, 1920. Serial No. 369,412.

To all whom it may concern:

Be it known that I, FRANK S. WAHL, a citizen of the United States, residing at North Tonawanda, in the county of Niagara 5 and State of New York, have invented new and useful Improvements in Internal-Combustion Engines, of which the following is a specification.

This invention relates to internal combustion engines and more particularly to an engine which is intended to operate under variations in atmospheric pressures or conditions such as an aeroplane engine.

The purpose of my invention is to provide 10 means whereby a greater volume of gaseous mixture is admitted to the cylinder than the ordinary piston displacement usually affords and to maintain the compression of this mixture in the cylinder constant under varying 15 atmospheric conditions by means which are controlled either manually, thermostatically or barometrically, or by a suitable combination of such controlling means. Such a provision is particularly suitable for aeroplane 20 engines inasmuch as engines for this service must travel in and utilize the atmosphere not only at sea level but also thousands of feet higher where the density of the air is much lower which renders the engine compression 25 variable at different levels and therefore yields variable power. An engine utilizing a fixed piston displacement is incapable of so filling the cylinder as to compensate for the varying densities of the atmosphere. By 30 handling a greater volume of the gaseous mixture than the normal piston displacement, as contemplated in the present invention, together with the regulator for adjusting the fuel intake to compensate for variation 35 in atmospheric conditions it is possible to maintain the compression of the mixture constant.

This application is a division of an application filed by myself November 30, 1917, 40 Serial No. 204,571 and patented April 27, 1920, No. 1,338,056.

In the accompanying drawings:

Figure 1 is a vertical section of one form 45 of internal combustion engine embodying my invention. Figure 2 is a vertical section showing a modification of my invention.

Similar characters of reference indicate corresponding parts in both views.

Referring to Fig. 1, 1 represents the 50 low base or frame of the gas or internal combustion engine which may be operated

by any explosive medium such as gas, gasoline or kerosene. Within this base is arranged a main or driving shaft 2 which in this instance is arranged horizontally and journaled in bearings 3, on the bottom of this base, or in any other suitable manner. Between its bearings this shaft is provided with a central crank 4 which projects from one side of the center of the same and two side cranks 5, 5, which project laterally from the axis of the shaft diametrically opposite to the central crank, this last-mentioned crank being arranged midway between the two side cranks.

6 represents an upright tubular guide which is mounted at its lower end on the upper part of the engine base or frame and 7 an upright pump cylinder arranged above the tubular guide and axially in line therewith and having an internal bore larger than the bore of the tubular guide. About midway of its height this tubular guide is provided with an exhaust passage or manifold 8 which is preferably of annular form and opens inwardly to the bore of this guide and is provided with an outlet 9 on its outer side, whereby the products of combustion may be discharged to the atmosphere or conducted to any other suitable place. For the purpose of cooling the engine, the tubular guide and the pump cylinder are provided with an enclosing shell 10 which forms a jacket 11 therebetween through which water or other cooling medium is circulated in a manner similar to that commonly practiced in engines as now generally manufactured. 12 represents a tubular cylindrical member which reciprocates lengthwise within the tubular guide and forms part of the means whereby the gaseous fuel or combustible mixture for operating the engine is drawn into the engine and compressed therein and also part of the means whereby the power to the exploding mixture is transmitted to the crank shaft. At its lower end this tubular member is arranged within the base and connected on diametrically opposite sides by means of two connecting rods 13 with the side cranks of the main shaft. At its upper end this tubular member is connected with a plunger or piston 14 which reciprocates vertically within the pump cylinder or barrel and forms part of the mixture pumping and compressing mechanism. The lower end of the tubular member 12 is open and its upper end is provided with means for feed-

ing the explosive charge into the same and also ignites the charge. Between its upper and lower end this member is provided with an exhaust or outlet for the products of combustion from the interior of this member into the exhaust manifold this exhaust of the tubular member being preferably constructed in the form of an annular row of comparatively narrow slots or openings 15. 16. 16 represents the power or firing piston reciprocating lengthwise within the tubular member and connected with the central crank of the main shaft by means of a pitman or connecting rod 17. The tubular member thus serves as the firing cylinder of the engine; the guide rod of the pump plunger also serves to deliver half of the power developed to the crank shaft; and the same also operates in conjunction with the firing piston and the exhaust manifold as the outlet valve mechanism, whereby the exhaust or outlet of the engine for the spent products of combustion is controlled.

The space in the pump cylinder above the pump plunger and the space within the upper part of the tubular member between the pump plunger and the firing piston, which last mentioned space forms the engine cylinder proper, are adapted to be placed in communication or cut off from communication by a valve mechanism which may be variously constructed. The valve mechanism shown is an example of one which may be used for this purpose and comprises a valve casting or cage 18 which is secured by means of a screw joint in a vertical opening formed centrally in the pump plunger and the top of the cylinder, and provided centrally with a port 19 leading from the upper part of the pump cylinder to the upper part of the firing cylinder and terminating at its lower end in a downwardly-facing conical main valve seat 20. 21 represents an outwardly-closing main intake valve of conical form adapted to engage the valve seat 20 and provided with an upwardly-projecting valve stem 22 which is guided in an upright guide sleeve 23 which is connected by a bridge 24 with the valve cage 18. The main intake valve is yieldingly held in its closed position by means of a spring 25 surrounding the valve stem 22 and bearing at one end against a shoulder on the guide sleeve 23 while its other end bears against a disk 26 mounted on the upper end of this valve stem.

On the upper head of the pump cylinder is mounted a controlling device which co-operates with the main intake valve for the purpose of aiding in opening the latter during the last part of the upward stroke of the pump plunger and the first part of the downward stroke of the engine piston for prolonging the period during which this valve is held open and therefore insuring a

maximum fuel charge for the machine. In the form of this controlling device which is shown in Fig. 1, the same comprises a controlling cylinder 74 arranged on top of the pump cylinder 7 and opening at its lower end into the latter while its upper end is provided with a check valve 78 which permits air to escape from this end of this cylinder but prevents entrance of the same, and a controlling piston 79 arranged in the controlling cylinder and connected with the upper end of the valve rod 22. During the downward stroke of the firing cylinder the intake valve 21 is held shut by the gaseous mixture therein which is being compressed and also by the upward pulling effect of the controlling piston 79 as the latter in its descent in the controlling cylinder produces a partial vacuum in the upper end of this cylinder, these combined forces being greater than the tension of the spring 25. The ascent of the controlling piston is comparatively free inasmuch as the check valve 78 at this time opens and permits the escape of the air from the upper end of the controlling cylinder, which enables the expanding burning gases in the firing cylinder to hold the main intake valve 21 shut during the upward stroke of the firing cylinder. When, however, the exhaust ports of the firing cylinder are opened by the firing piston during the last part of the firing or expansion strokes of these members and the pressure within the firing cylinder drops, due to the escape of the spent gases, then the pressure of the spring 25 together with the pressure of the compressed charge of gas in the upper end of the pump cylinder opens the main valve 21 and this gas rushes into the firing cylinder and fills the same as the burnt gas escapes therefrom.

On the lower part of the pump cylinder, the same is provided with two fuel supply sections 35 and 350 of a fuel supply conduit or passage which communicates with a carburetor or any other source of supply from which the explosive mixture is drawn and two delivery sections 36, 37 one of which 36 leads into the upper end of the pump cylinder and the one 37 opening by a lower branch passage 38 into the lower end of this cylinder and by an upper branch passage or port 39 into this cylinder at a place between its upper and lower ends. Between the supply conduit section 35 and the delivery conduit section 36 is arranged an inwardly facing valve seat 390 and between the supply conduit section 350 and the delivery conduit section 37 is arranged an inwardly facing valve seat 40. 41, 42 represent two inwardly-opening poppet valves which are adapted to engage with the valve seats 40, 390, respectively, and are guided in their movements by means of upright valve stems 43, 44, projecting downwardly. 130

respectively, from the undersides of these valves and guided in tubular ways 45, 46, on the adjacent part of the engine body, as shown in Fig. 1.

5 Any suitable means may be provided for igniting the combustible charge within the firing cylinder at the proper time, those shown in Fig. 1 being constructed as follows:

70 71 represents the central terminal of the 10 spark plug which is provided with an upwardly extending brush rod 72 which slides in contact with a stationary metal disk or plate 73 connected with a binding post 74. This plate and binding post are mounted on 15 a tubular insulating cap 75 secured to the upper end of the pump cylinder. One side of the electric source is grounded on the metal parts of the engine so as to connect with the other terminal 76 of the spark plug 20 and the other side of the source connects with the binding post 74, and during the operation of the engine the brush rod 72 by sliding on the plate 73 keeps the terminals 71, 76 in the electric circuit for producing 25 the spark for igniting the charge.

When the parts of the engine are in the position shown in Fig. 1, the firing or working piston is in its uppermost position, the firing cylinder and plunger are in their lowest 30 position, the controlling piston is in its lowermost position, the main intake valve and the check valves are closed and the exhaust ports of the firing cylinder are arranged below the firing piston and the exhaust manifold. At this time, during the normal operation of the engine, a charge 35 of gaseous fuel or mixture is compressed between the firing piston and the upper part of the firing cylinder and a partially compressed charge of fuel is contained in the lower part of the pump cylinder. Upon 40 separating the firing cylinder the latter together with the pump plunger will be raised and the firing piston will be depressed and a pressure is exerted against the main intake valve which aids in holding the same shut. During this movement of the pump plunger and firing cylinder and piston the cranks 45 of the main shaft operate on diametrically opposite sides of the latter and the same is turned with a working impulse without however sustaining any shock or undue lateral pressure.

50 Immediately after the pump plunger has effected the initial part of its upward movement in the pump cylinder this plunger closes the upper branch passage 39 and produces a suction through the lower branch passage 38 into the lower end of the pump cylinder so that the check valve 41 is opened and a portion of the gaseous mixture is drawn from the carburetor into the lower end of the pump cylinder. After the pump plunger has passed above the upper branch

55 passage 39 part of the gaseous mixture is drawn through both the lower and upper branch passages 38, 39 into the lower end of the cylinder until the plunger reaches the upper end of its stroke. During the subsequent downward movement of the plunger the check valve 41 is closed and the gaseous mixture within the lower part of the cylinder is compressed until the pump plunger passes 60 below and uncovers the upper branch passage 39 at which time the compressed charge or mixture passes from the lower end of the pump cylinder through the lower and upper branch passage 38, 39 into the pump cylinder above the plunger. During the downward movement of the plunger the same also draws an additional quantity of gaseous mixture past the valve 42 and passage sections 35 and 36 into the upper end of the pump cylinder. The two quantities of gas, one 65 drawn directly into the upper part of the pump cylinder during the downward movement of the latter and the other drawn indirectly into this end of the cylinder during the upward and downward stroke of the 70 pump plunger are subsequently compressed in the upper part of the pump cylinder, during the next following upward stroke of the 75 pump plunger.

80 The pressure of the expanding burning mixture in the firing chamber is greater than the pressure of the gas mixture within the upper end of the pump cylinder, this being partly due to the fact that the latter is of 85 larger cross sectional area than the firing cylinder. During the last part of the firing 90 stroke of the engine during which the firing piston is in its lower position and the pump plunger and firing cylinder in their upper 95 position, the exhaust ports of the firing cylinder register with the exhaust manifold and the firing piston uncovers these 100 exhaust ports and is arranged below the same. The instant this occurs the products of combustion of the burned mixture 105 escape from the lower end of the firing chamber through the exhaust ports thereof into the exhaust manifold. This causes the pressure in the firing cylinder to drop 110 immediately below that of the compressed 115 gases within the upper end of the pump cylinder whereby the predominating pressure of the fresh gases in the pump cylinder aided by a spring 25 forces the intake valve 120 21 to open and causes the live or fresh charge of gaseous fuel to pass downwardly into the firing cylinder.

125 Immediately after the firing piston has reached its lowermost position and the firing cylinder its uppermost position the movement of these parts is reversed and during the initial part of the subsequent upward movement of the firing piston and the downward movement of the firing cylinder 130 the exhaust ports are again closed by the

- spring piston so that the fresh charge of the explosive mixture within the firing cylinder is compressed during the remaining portion of their compression strokes. When the firing cylinder and firing piston reach the end of their downward and upward strokes respectively, the compressed mixture between the same is ignited and the next cycle of operations is repeated as above described.
- 10 When this engine is used for propelling an aeroplane the range of travel which varies anywhere from sea level to high altitudes, it is desirable to provide means for varying the admission of gaseous mixture to the engine in accordance with the changes in temperature of the engine and variations in the condition of atmosphere in which the aeroplane for the time being is traveling. These means are preferably associated with the check valves 41, 42 in the supply conduits and may be controlled either manually or thermostatically or barometrically. The means shown in connection with the check valve 41 in Fig. 1 are manually controlled and comprise a spring 55 surrounding the lower end of the valve stem 43 and bearing at its upper end against the lower end of the valve stem guide 45 while its lower end bears against a screw nut 56 on the threaded lower end of this valve stem. By turning this adjusting screw nut so that it moves either up or down on its valve stem, the tension of the spring 55 which resists the opening movement of this check valve may be regulated so as to admit a greater or a lesser quantity of gaseous mixture through this particular conduit into the engine by the action of the pump plunger. By this means the amount of the mixture may be varied manually to suit the altitude at which the aeroplane is traveling, the tension on the spring 55 being made lighter so that a larger volume of mixture is admitted when the aeroplane is traveling at a high altitude and the atmosphere is less dense and the tension of the spring may be increased so that the check valve 41 opens less freely and therefore permits a smaller volume of mixture to enter the engine when the aeroplane is traveling at a lower altitude where the atmosphere is more dense.
- 15 This same effect may be produced automatically by means which are responsive to variations in the density of the atmosphere. Such a mechanism is shown in connection with the check valve 410, in Fig. 2, and comprises a shell or casing 57 mounted on the base or other stationary part of the engine and divided by a movable diaphragm or partition 58 into a lower closed air chamber 59 and an upper vented air chamber 60 which communicates with the outer atmosphere by means of openings 61 in the top of this chamber. From the central part of this diaphragm a shifting rod 62 extends op-
- wardly through a guide 63 in the top of the upper air chamber, and a spring 64 is employed for connecting the upper end of the shifting rod 62 with the lower end of the stem 43 of the check valve 410. In low altitudes the greater pressure of the air entering the upper chamber 60 through the openings 61 causes the diaphragm to be depressed and the spring 64 to be strained to a greater extent so as to increase the resistance of the check valve 410 against opening under the suction action of the pump plunger, thereby reducing the amount of gaseous mixture which is drawn into the engine. When however, the engine is traveling in high altitudes where the air is less dense the reduced pressure of the air against the upper sides of the diaphragm causes the tension of the spring 64 to become relaxed accordingly and thereby permit the check valve 410 to open easier and allow a proportionately increased volume of gaseous mixture to be drawn by the pump plunger into the engine. The barometric regulator therefore automatically adapts the supply of fuel to the engine in accordance with the requirement under different atmospheric conditions.
- 20 In order to steady the movement of the diaphragm a spring 65 is preferably mounted on the rod 62 between the top of the casing 57 and the diaphragm so that it operates to assist in depressing the diaphragm.
- 25 The head 24 forming the upper end of the firing cylinder 12 and also part of the pump plunger 14 is provided on its upper side with heat radiating ribs or fins 66 which carry away some of the heat developed in the firing cylinder and warm the incoming gas in the upper part of the pump cylinder so as to thoroughly vaporize the fuel and promote rapid ignition of the same.
- 30 In Fig. 1 are also shown means for regulating the explosive mixture supply to the engine which are responsive to variations in the thermal conditions in the engine as well as fluctuations in the density of the atmosphere. It is well known that a warm mixture cannot be compressed to the same degree as a cold one of the same volume. To thoroughly vaporize the fuel, especially the lower grades, requires considerable heat. In order to obtain the highest efficiency, an engine should be capable of using a hot mixture in which the fuel has been thoroughly vaporized and at the same time maintain its degree of compression constant. The example of means in Fig. 1 showing such a thermostatic control combined with a barometric control is constructed as follows:
- 35 85 represents a barometric shell or casing mounted on a stationary part of the engine and divided by a flexible diaphragm or partition 86 into a lower sealed air chamber 87 and an upper vented air chamber 88 which is open to the atmosphere through

perforations 84 in the top of the chamber 88. 89 represents a shifting rod guided in the upper part of the shell, and 90 a spring surrounding this rod and interposed between the top of the shell and the diaphragm so as to yieldingly hold the latter in a depressed position. 91 represents a regulating lever pivoted at one end to the upper end of the diaphragm rod. To the central part of this lever is connected a spring 92 which is in turn connected with the lower end of the valve rod 44 of the check valve 42 arranged in the fuel supply conduit 35 of the engine.

96 represents a pipe or conduit forming part of the system whereby water is circulated around various heated parts of the engine for the purpose of cooling the same. In this water conduit is arranged a thermostatic rod or element 97 which is adapted to expand and contract in response to a rise and fall in the temperature of the water passing through the circulating conduit. One end of this thermostatic rod is fixed on the pipe, as shown at 98, and the other is connected with a rock arm 99 arranged within the pipe 96 and mounted on a rock shaft 100 journaled in suitable bearings on this pipe. Outside of the latter the rock shaft 100 is provided with a rock arm 101 which is connected by a rod 102 with the other end of the lever 91.

As the temperature of the engine increases, the temperature of the explosive mixture is also raised. As a result the thermostatic element 97 in the water conduit expands and shifts the regulating lever 91 so as to reduce the tension on the spring 92 and permit the check valve 42 to open easier. Any changes

in the density of the air will cause the diaphragm 86 to rise or fall and thereby also lessen or increase the tension of the spring 92 and either increase or decrease the volume of mixture which is permitted to enter the engine.

I claim as my invention:

1. An internal combustion engine comprising a fuel supply conduit, a movable valve for controlling said conduit, and means for adjusting the extent of opening of said valve, comprising a spring connected with said valve, a shell containing two chambers which are separated by a flexible diaphragm which is connected with said spring, one chamber being open to the atmosphere and the other closed to the atmosphere, and a thermostatic element responsive to changes in the temperature of the engine and operatively connected with said valve.

2. An internal combustion engine comprising a cylinder, a fuel supply conduit, a cooling system having a water conduit, a valve in said supply conduit, and means for controlling the opening of said valve, comprising a shell, a flexible diaphragm dividing said shell into two compartments one of which is closed and the other opened to the atmosphere, a guide rod connected with said diaphragm, a spring connected with said valve, a lever connected with said rod and spring, a thermostatic element arranged in said water conduit and having one end fixed, an inner rock arm connected with the other end of said thermostatic element, a rock shaft carrying said inner arm and an outer arm connected with said rock shaft and with said lever.

FRANK S. WAHL.
